UNITED STATES PATENT OFFICE.

JOSEPHINE S. KEATOR, OF KINGSTON, NEW YORK.

IMPROVEMENT IN SHUTTER-FASTENINGS.

Specification forming part of Letters Patent No. **156,486**, dated November 3, 1874; application filed October 17, 1874.

To all whom it may concern:

Be it known that I, Mrs. JOSEPHINE S. KEATOR, of Kingston, in the county of Ulster and State of New York, have invented a new and useful Improvement in Blind and Shutter Fastening, of which the following is a specification:

This invention relates to a new and improved device for fastening window blinds or shutters; and consists of an angular hook, which is held in position by the window-sash, the construction and arrangement being as hereinafter more fully described.

In the accompanying drawing, Figure 1 is a top view, looking down from the line *x x* of Fig. 2. Fig. 2 is a cross-section of Fig. 1 taken on the line *y y*.

Similar letters of reference indicate corresponding parts.

A represents the window blind or shutter. *B* is the sash. *C* is the fastening-hook, which engages with the staple *D* of the blind. The butt-end of this hook is turned to form a right angle, *E* being the portion so turned. *F* is a plate, which is fastened to the window-sill. The hook is secured to this plate by the rivet *G*. This plate may be dispensed with, and the hook may be fastened by a screw directly to the sill, if desired. In such a case the hook

would be bent upward to raise the end somewhat from the sill. *H* is a lip, which projects upward from the portion *E*, which bears against the sash when an effort is made to unfasten the blind from the outside. *I* is the lower rail of the sash, which bears against the lip *H*.

The window-blind is, therefore, safe when the sash is closed.

When the sash is up the hook may be secured by a pin inserted in, or a button fastened to, the window-sill, or in any suitable manner.

This is a cheap and simple device, and one entirely effective for fastening the blinds or shutters of windows.

Having thus described my invention, I claim as new and desire to secure by Letters Patent—

1. A blind or shutter fastening consisting of the hook *C* with an angular portion, *E*, substantially as described.

2. The lip *H*, in combination with a blind-fastening hook, substantially as shown and described.

JOSEPHINE S. KEATOR.
